UNITED STATES PATENT OFFICE.

SYLVESTER L. JOINER, OF MCGREGOR, TEXAS.

COMBINED GRAIN-DOOR STRIP AND SIDE-DOOR-POST PROTECTOR.

Application filed April 7, 1926. Serial No. 100,466.

The invention relates to a combination box car grain door strip and side door post protector.

The object of the invention is to provide a simple, practical and efficient combination grain door strip and side door post protector of strong, durable and comparatively inexpensive construction adapted to be readily applied to a box car interiorly 10 thereof at opposite sides of the door opening and equipped with a metal housing adapted to protect the side post of box cars and also to support a wooden strip in position for enabling the boards of a grain door 15 to be secured to it without the nails or other fastening means penetrating the side post of the car.

Another object of the invention is to provide a combined grain door strip and door 20 post protector adapted to last the full life of a box car and capable of enabling the wooden strip which receives the fastening devices of the grain door to be readily replaced when necessary and capable of bracing 25 and supporting the wooden strip at opposite sides thereof and of enabling the wooden strip to last for a considerable length of time so that it will not require renewal until the box car is overhauled or rebuilt.

It is also an object of the invention to provide a grain door strip and door post 30 protector adapted to serve as a shield or protection to prevent the hand trucks which are employed for loading and unloading the car from coming in contact with and cutting or otherwise injuring the wooden door post 35 of the car and which will present smooth rounded surfaces at the exposed corners of the grain strip for contact with the hand trucks or other objects.

With these and other objects in view, the invention consists in the construction and novel combination and arrangement of parts hereafter fully described, illustrated in the 45 accompanying drawings and pointed out in the claim hereto appended, it being understood that various changes in the form, proportion and minor details of construction, within the scope of the claim, may be 50 resorted to without departing from the spirit or sacrificing any of the advantages of the invention.

In the drawings:—

Figure 1 is a longitudinal sectional view 55 of a portion of a car showing one of the side doors thereof in elevation equipped

with combined grain door strips and side post protectors constructed in accordance with this invention.

Fig. 2 is a central longitudinal sectional view 60 through one of the grain door strips, the grain door strip being broken away to enable it to be shown on a larger scale.

Fig. 3 is a transverse sectional view of the grain door strip and side post protector taken on the line 3—3 of Fig. 2.

Fig. 4 is a similar view taken on the line 4—4 of Fig. 2.

In the accompanying drawing in which is illustrated the preferred embodiment of 70 the invention the combined grain door strip and side post protector consists of a metallic housing constructed of any suitable metal and composed of spaced side bars 1 and integral connecting transverse bars or portions 75 2 arranged at the ends of the center of the metallic housing as clearly illustrated in Fig. 2 of the drawing but any desired number of the integral connecting cross pieces 2 may of course be employed as will be readily 80 understood. The side bars 1 of the metallic housing are substantially quadrant shaped in cross section to present flat inner and rear faces 3 and 4 and smooth rounded surfaces 85 5 at the exposed corner portions as clearly illustrated in Figs. 3 and 4 of the drawings. The said side bars may be made of any desired size and are preferably castings and may be made either solid as shown or cored 90 out to provide a hollow relatively light construction where desired. The metallic housing is secured to the interior of the car 6 at opposite sides of the door opening 7 by screws 8 which have their heads arranged in flush relation with the outer faces of the 95 side bars of the metallic housing. The side bars are provided with openings 9 which have enlarged tapered outer portions 10 to permit the heads of the screws to be countersunk in the side bars of the metallic strip. The grain door strip and side post protector 100 extends from the top to the bottom of the door opening 7 as clearly shown in Fig. 1 and it may be made of any desired dimensions as will be readily understood.

The spaced or longitudinal opening in the metallic housing between the side bars 1 receives a wood filler strip 11 rectangular in cross section as clearly shown in Figs. 3 and 4 of the drawing and provided at its ends and center with recesses 12 and 13 for the reception of the cross pieces of the metallic 105 110

housing whereby the wood filler strip is interlocked with the metallic housing. The wood filler strip extends from the front faces of the side bars 1 to the rear faces thereof except that the recesses 12 and 13 for the reception of the cross pieces 2 and the nails 14 or other fastening devices for securing the boards 15 of the grain door to the sides of the car are driven into the wood filler strip. By securing the grain door to the wood filler strip the side posts are protected from the fastening devices of the grain door and the latter may be removed without injuring the door posts or sides of the car and the wood filler strips may be used repeatedly and will last until the car requires rebuilding or overhauling. The metallic housing may be constructed to receive a wood filler strip of any desired dimensions and while for convenience of illustration the boards 15 of the grain door are shown covering only the lower half of the door opening 7 it will be clear that the grain door strip will enable the boards to be extended upwardly from the bottom of the car as far as desired. The device is adapted to protect the door posts and the sides of the car at the door opening and will materially increase the life of the car and will lessen ex-

pense of handling grain by avoiding the injury which ordinarily results from the use of grain doors of the ordinary construction and from the contact of hand trucks and other objects with the door posts.

What I claim is:

A combined grain door strip and side door post protector located interiorly of the car at opposite sides of the door opening and comprising a metallic housing composed of spaced longitudinal side bars and integral cross pieces connecting the side bars and arranged in flush relation with the rear face thereof, the side bars being provided with openings for fastening devices for securing the metallic housing to the car, said side bars presenting smooth rounded surfaces at the front exposed corners, and a wood filler strip fitting and filling the space between the side bars and provided at its inner or rear face with recesses conforming to the configuration of and receiving the said cross pieces whereby the filler strip is interlocked with the metallic housing, said filler strip being arranged to receive the fastening devices of a grain door.

In testimony whereof I have hereunto set my hand.

SYLVESTER L. JOINER.
